UNITED STATES PATENT OFFICE.

CHARLES F. TROMMER, OF NEW YORK, N. Y., ASSIGNOR TO A. WITTNauer CO., OF NEW YORK, N. Y., A CORPORATION OF NEW YORK.

WRIST-WATCH.

1,313,843.

Specification of Letters Patent. Patented Aug. 19, 1919.

Application filed November 27, 1918. Serial No. 264,327.

To all whom it may concern:

Be it known that I, CHARLES F. TROMMER, a citizen of the United States, and a resident of the city of New York, Glendale, borough 5 of Queens, in the county of Queens and State of New York, have invented a new and Improved Wrist-Watch, of which the following is a full, clear, and exact description.

10 Among the principal objects which the present invention has in view are: to facilitate the operation of installing and removing an article of the character mentioned in service; to avoid loss of the article; and to 15 coördinate the elements of the construction for improving the appearance of the article.

Drawings.

Figure 1 is a perspective view of an article 20 of the character mentioned, the view showing the back of a watch case and the opening ends of the bracelet members;

Fig. 2 is a detail view showing in section and on an enlarged scale, the arrangement 25 of the connected ends and clasp for holding the same, the section being taken as on the line 2—2 in Fig. 1;

Fig. 3 is a detail view in perspective showing a modified form of the clasp ends;

30 Fig. 4 is a sectional view thereof, the section being taken as on the line 4—4 in Fig. 3.

Description.

As seen in the drawings, a watch case 9 is 35 furnished with thin lateral rigid extensions 10. The extensions 10 have hinge knuckles 11, beside which in matched relation are disposed hinge knuckles 12 formed on the clasp sections 13 and 14. The sections 13 and 14 40 are normally closed upon each other by springs 15, suitably arranged between the jointed edges and at the hinge connection. By reference to Fig. 1 it will be noticed that the back of the watch case 9, the side extensions 10, and the clasp sections 13 and 14 45 form an encircling means for the wrist of the user. Several methods may be employed for preventing the sections 13 and 14 pressing too closely upon the wrist of the wearer.

50 Two forms are shown in the drawings, the one providing a hinged latch 16, which as best seen in Fig. 2 of the drawings, has a pintle 17 extended from the under side thereof for engaging any one of a series of sockets 55 18. The latch 16 is permanently attached to one of the clasp sections, a bracket

19 being extended from the side of said section. In the drawings, the bracket 19 is shown as extended from the side of the section 13.

60 The latch 16 has at the free end thereof, a spring hook 20, which resiliently engages the opposite edge of the section 13 when the pintle 17 rests within one of the sockets 18. It is obvious that when the latch 16 is fastened, the sections 13 and 14 are held in permanent relation. The sockets 18 are sufficiently close to provide for all the usual 65 adjustments of the clasps 13 and 14 to different sizes of wrists. Where closer adjustment is desired, however, the hinge clasp is replaced by a friction loop 21, which is permanently attached to the section 13 to frictionally engage the free end of the section 14. The engagement of the loop 21 with the 70 end of the section 14 is such as to permit the sections to be drawn apart or compressed manually, the said loop resisting the springs 15 in their normal effort to close said clasp sections.

Claims.

1. A wrist watch comprising a watch case having integral thin lateral rigid extensions; a plurality of rigid clasp sections, said sections being pivotally attached to said lateral extensions, the free ends of the said clasp sections being arranged in overlapping sliding relation, the back of the watch case, the said extensions and the said clasp sections forming an encircling means for the wrist of the wearer; means for normally contracting said clasp sections; and means for holding said clasp sections in relatively adjusted positions.

2. A wrist watch comprising a watch case having integral thin lateral rigid extensions; a plurality of rigid clasp sections, said sections being pivotally attached to said lateral extensions, the free ends of the said clasp sections being arranged in overlapping sliding relation, the back of the watch case, the said extensions and the said clasp sections forming an encircling means for the wrist of the wearer; means for normally contracting 105 said clasp sections; and means for holding said clasp sections in relatively adjusted positions, said means embodying a detent member mounted on one of said sections for engaging the opposite section.

3. A wrist watch comprising a watch case having integral thin lateral rigid exten-

sions; a plurality of rigid clasp sections, said sections being pivotally attached to said lateral extensions, the back of the watch case, the said extensions and the said clasp sections forming an encircling means for the wrist of the wearer; means for normally contracting said clasp sections; and means for holding said clasp sections in relatively adjusted positions, said means embodying a latch hingedly connected with one of said sections and adapted when locked to hold the other of said sections.

4. A wrist watch comprising a watch case having integral thin lateral rigid extensions; a plurality of rigid clasp sections, said sections being pivotally attached to

said lateral extensions, the back of the watch case, the said extensions and the said clasp sections forming an encircling means for the wrist of the wearer; means for normally contracting said clasp sections; and means for holding said clasp sections in relatively adjusted position, said means embodying a plurality of sockets formed adjacent the end of one of said sections, a latch pivotally mounted on the other of said sections adjacent the end thereof, said latch having a pin-tle for engaging said sockets to hold said sections from being contracted upon the wrist of a wearer. 20 25

CHARLES F. TROMMER.
